UNITED STATES PATENT OFFICE.

LUTHER H. BRAUN, OF STEUBENVILLE, OHIO, ASSIGNOR OF ONE-HALF TO FRANK X. STECKER, OF STEUBENVILLE, OHIO.

RAIL-JOINT.

1,227,874.

Specification of Letters Patent. Patented May 29, 1917.

Application filed January 31, 1917. Serial No. 145,634.

To all whom it may concern:

Be it known that I, LUTHER H. BRAUN, a citizen of the United States of America, and resident of Steubenville, county of Jefferson, 5 and State of Ohio, have invented certain new and useful Improvements in Rail-Joints, of which the following is a specification.

This invention relates broadly to rail joints, and more particularly to a coupling for the adjacent ends of railway rails.

The primary object of the invention is to provide a comparatively simple and inexpensive coupling for the ends of railway 15 rails in which the use of the usual connecting bolts is wholly dispensed with and which affords positive means for maintaining the rail ends in proper relation.

A further object of the invention is to provide a device of the character mentioned 20 which effectually guards against longitudinal creeping of the rails.

With these and other objects in view, the invention resides in the features of construction, arrangement of parts and combinations 25 of elements which will hereinafter be fully described, reference being had to the accompanying drawings, forming a part of this specification, in which—

30 Figure 1 is a perspective view of the invention applied;

Fig. 2 is a partial longitudinal section of the rail chair, showing the web-embracing members in position;

35 Fig. 3 is a central longitudinal section of the invention applied;

Fig. 4 is a transverse section on line 4—4, Fig. 2; and

40 Fig. 5 is a perspective view of the web-embracing members.

Referring to said drawings, in which like designating characters distinguish like parts throughout the several views—

1 and 2 indicate the integral parallel members 45 of a rail-embracing clamp, each of said members corresponding generally in cross-sectional form to a common type of angle bar except that it has the upright rail-web-engaging portion 3 thereof of slightly less

50 height than the normal height of such angle bar to afford a space between its upper edge and the shoulder of an engaged rail. Said members 1 and 2 are joined at a point substantially midway between the ends of the 55 member 1 by an integral abutment 4 having

the form of an isosceles triangle, the apex of which projects above the edges of said portions 3. The oppositely facing sides of said abutment may be disposed at any appropriate angle, as 45°, to the base thereof 60 and are adapted to receive in abutting relation thereto the ends of adjacent railway rails 5 and 6 which have sections of triangular form cut therefrom, removing portions of their webs and bases, such removed 65 sections corresponding substantially in form and size to that of one-half said abutment divided vertically through its apex, as is most clearly shown in Fig. 3.

The member 2 of the rail-embracing clamp 70 is of less length than the member 1, one end thereof being in the same vertical plane with the corresponding end of said member 1 and the other end thereof terminating in the inclined plane of the oppositely facing side of 75 the abutment 4, as shown in Figs. 2 and 5. A separate member 7 is complementary to said member 2, having its inner end inclined to correspond with and to assume mitering relation to the inclined end of the latter. 80 Said member 7 constitutes a locking element whereby longitudinal movement of the rail-embracing clamp in a forward direction is prevented, the same coöperating with a shoulder 8 presented by an inwardly extending 85 wall 9 formed integral with one of the side portions 10^a of a rail chair 10 which is designed to closely embrace the adjacent rail ends and the clamp.

Said rail chair 10 is formed in a single 90 piece and consists of a flat base 10^b adapted to be mounted upon the usual crossties, and the opposite side portions 10^a, the latter being shaped to conformably embrace the rail ends and the clamp which comprises the 95 members 1 and 2, as aforesaid, and also the locking element 7, said side portions having inwardly directed terminal edge 10^c adapted to fill the spaces between the upper edges of the members 1 and 2 and the overhanging 100 shoulders constituted by the under sides of the rail-head, as is clearly shown in Figs. 1 and 4.

The rail chair 10 preferably has an integral base extension 10^d formed at one end 105 thereof, or, if desired, such an extension may be provided at each end of the chair. Said extension is provided with notches or recesses 11 in the edges thereof for the reception of securing spikes, as 12. 110

In practice, the application of the device is preferably accomplished in the following manner: The locking element 7 is first introduced within the rail chair 10 and is held 5 therein in proper position, as by hand or by means of a suitable tool, until the end of rail 6 has been entered within said chair a distance slightly past the outer end of said element; whereupon the latter will be prevented by said rail from falling laterally 10 inward. The chair is then slipped forward over said rail until the end of the latter occupies a position substantially midway between the chair ends. Then the clamp comprising 15 the members 1 and 2 is slipped upon the end of rail 5 to a position wherein the inclined end of the latter seats against the adjacent face of the abutment 4, whereupon the clamp and said rail 5 are together introduced 20 within the end of chair 10 opposite that occupied by the end of rail 6, the inward movement of the clamp and the rail 5 being continued until the abutment seats against said rail 6; or, if said rail 6 has been projected past the midway point of the chair, said movement is continued, driving rail 6 outward, until the inclined end of the locking element 7 is engaged by the inclined end of the clamp member 2; or, in case said 25 locking element has been advanced beyond its normal seating position, as is liable to occur due to frictional engagement therewith of rail 6 when the latter is being introduced, said movement is continued, 30 forcing said locking element outward, until the outer end of the latter engages the shoulder 8 presented by the inwardly extending wall 9 of the chair.

As is obvious, the positioned clamp is positively locked against forward movement by 40 the locking element 7 which is interlocked as aforesaid with the rail chair 10, which latter is immovably attached to the underlying crossties. Consequently, the rail 5 having its end seated against the abutment 4 of said clamp is positively maintained against forward creeping movement. It will be noted, however, that the device does not maintain the rails, or either of them, against 45 longitudinal creeping movement in an outward direction—that is, does not prevent movement of said rails in directions away from each other. Such movement is however prevented in practice by the obvious 50 expedient of disposing adjacent joints in reversed relation—that is, by mounting adjacent chairs in reverse positions.

What is claimed is—

1. The combination with the adjacent ends 60 of railway rails, each of which has a portion of the web and base thereof cut away, of a rail clamp comprising a pair of parallel rail-embracing members and an integral abutment joining said members substantially midway between the ends of said 65

clamp and adapted for receiving said rail ends thereagainst, one of said members having one end of shorter length than the corresponding end of the other member, a locking element complemental to said shorter end and adapted to engage the latter, and a rail chair adapted to occupy embracing relation to said clamp and to said locking element and to support said rail ends, said chair having a shoulder adjacent to one end 70 thereof against which the outer end of said locking element seats and which prevents longitudinal movement of said element in an outward direction. 75

2. The combination with the adjacent ends 80 of railway rails, each of which has a portion of the web and base thereof cut away, of a rail clamp comprising a pair of parallel rail-embracing members which are rigidly united intermediate their ends by a transverse connecting member, said connecting member being adapted for receiving said rail ends in seating relation thereto, and a rail chair adapted to receive said clamp and the embraced rail ends within its embrace, 85 said clamp having an inturned portion at one end thereof affording a shoulder whereby the extent of longitudinal movement of said clamp in one direction is limited. 90

3. The combination with the adjacent ends 95 of railway rails, each of which has a portion of the web and base thereof cut away, of a rail clamp comprising a pair of parallel rail-embracing members which are rigidly united intermediate their ends by a transverse connecting member, said connecting member being adapted for receiving said rail ends in seating relation thereto, said rail-embracing members having their rail-web-engaging portions of less height than 100 the rail web, and a rail chair adapted to receive said clamp and the embraced rail ends within its embrace, said chair having inturned terminal edges snugly occupying the spaces between the upper edges of said rail-embracing members and the overlying shoulders of the rails, and said chair also having a portion at one end thereof preventing outward movement of said clamp in 105 one direction from its properly seated position. 110

4. The combination with the adjacent ends 115 of railway rails, each of which has a portion of the web and base thereof cut away, of a rail clamp comprising a pair of parallel rail-embracing members and an integral abutment joining said members substantially midway between the ends of said clamp and adapted for receiving said rail ends thereagainst, one of said members having one end of shorter length than the corresponding end of the other member, a locking element complemental to said shorter end and adapted to engage the latter, said rail-embracing members having their rail- 120

125

130

web-engaging portions of less height than the rail web, and a rail chair adapted to receive within its embrace said clamp and said locking element, together with the 5 em braced rail ends, said chair having inturned terminal edges disposed in underlying seated relation to the shoulders of the rails and also having at one end thereof an inturned portion affording a shoulder whereby said 10 locking element is maintained against outward movement from its operative position.

5. The combination with the adjacent ends of railway rails, each of which has a portion of its web and base removed, of a rail clamp 15 comprising parallel members between which said rail ends are received, and a transverse member connecting said parallel members at a point intermediate their ends, said trans- 20 verse member being shaped to constitute an abutment against which said rail ends comfortably seat, and a rail chair for embracing and supporting said clamp and said rail ends and having a portion adapted to be engaged by said clamp whereby relative 25 movement of the latter from its operative position is prevented.

6. The combination with the adjacent ends of railway rails, each of which has a portion of its web and base removed, of a rail clamp 30 comprising parallel members between which said rail ends are received, a transverse member connecting said parallel members at

a point intermediate their ends, said trans- 35 verse member being shaped to constitute an abutment against which said rail ends com- fortably seat, a rail chair for embracing and supporting said clamp and said rail ends, said chair having an inturned portion at one end thereof forming a shoulder, and a lock- 40 ing element complementing one of said rail- embracing members and adapted to be inter- posed between an end of the latter and said shoulder whereby relative movement of said clamp from its operative position is pre- 45 vented.

7. The combination with the adjacent ends of railway rails, of a rail clamp comprising parallel members between which said rail ends are received, and a transverse member connecting said parallel members at a point 50 intermediate their ends, said transverse member being shaped to constitute an abut- ment for limiting longitudinal movement of said rails, and a rail chair for embracing and supporting said clamp and said rail ends, 55 said chair being provided with means whereby relative movement of the clamp from its operative position is prevented.

In testimony whereof, I affix my signature in presence of two subscribing witnesses. 60
